[57] **CLAIM**

The ornamental design for a mallet head, as shown and described.

DESCRIPTION

FIG. 1 is a perspective view of a mallet head showing my new design, the handle, housing compartment and ball shown in broken lines for illustrative purposes only; FIG. 2 is a top plan view thereof; FIG. 3 is a right side elevational view thereof, the opposite side being identical; FIG. 4 is a front elevational view thereof, the opposite side being identical; and, FIG. 5 is a cross-sectional view taken along line 5—5 of FIG. 3. The undisclosed bottom view is unornamented.
